UNITED STATES PATENT OFFICE.

ROBERT MIEHLE, OF CHICAGO, ILLINOIS.

FUEL-REGULATOR FOR STEAM-BOILERS.

1,092,781.

Specification of Letters Patent.

Patented Apr. 7, 1914.

Application filed April 11, 1907. Serial No. 367,618.

To all whom it may concern:

Be it known that I, ROBERT MIEHLE, a citizen of the United States, residing at Chicago, county of Cook, and State of Illinois, have invented certain new and useful Improvements in Fuel-Regulators for Steam-Boilers, of which the following is a full, clear, and exact specification.

This invention relates to fluid fuel regulators for steam generators, and more particularly for the flasher type of boilers or generators in which it is desirable to maintain a uniform pressure notwithstanding wide variations in the amount of steam used, and hence it is necessary to vary the fuel supply in accordance with variations in the steam pressure.

One of the objects of this invention, therefore, is to provide improved and efficient means for regulating the fuel supply by variations in the steam pressure as contradistinguished from the steam temperature.

Another object of the invention is to provide improved means for reducing the fuel supply when the steam pressure falls below a certain degree whereby the fuel will be economized and the fire will be prevented from injuring the generator when the water supply becomes insufficient to protect the generator.

In devices of this character it is, of course, desirable to have the mechanism so set that the fuel will be reduced or shut off when the steam pressure reaches a certain maximum, as well as when it reaches a certain minimum, and where these extremes are very wide apart, there might be instances when the amount of water or steam in the generator would not be sufficient to enable the maximum heating capacity of the fuel to raise the pressure to the shut-off point, and as a consequence, in that event, the generator would be damaged by the fire, the pressure remaining between the maximum and minimum shutting-off degrees.

The invention has for its further object, therefore, to provide improved means whereby this objectionable result will be prevented.

Another object of the invention is to provide improved and efficient means whereby the operator may at will either reduce or increase the fuel supply regardless of the degree of steam pressure and its action upon the automatic controlling devices.

A still further object of the invention is

to provide improved means for preventing the fumes from the vaporizing fuel from escaping from the burner nozzle and passages between the retort or gas generator and the nozzle when the pressure in the nozzle or such passages falls so low that the gas will not be projected from the nozzle into the burner, such escaping fumes being too "lean" a mixture to burn, and yet sufficiently rich in hydro-carbon vapor to produce an objectionable odor.

With a view to the attainment of these ends and the accomplishment of certain other objects which will hereinafter appear, the invention consists in the features of novelty which will now be described with reference to the accompanying drawings, and then more particularly pointed out in the claims.

In the said drawings:—Figure 1 is a side elevation of a steam generator embodying this invention, showing the same as applied to a flasher boiler of the type usually employed on motor vehicles. Fig. 2 is an enlarged detail vertical sectional view of the gas nozzle and a part of the burner. Fig. 3 is an end view of the nozzle cap. Fig. 4 is an enlarged detail view of an indicator hereinafter described. Fig. 5 is a vertical sectional view of the fuel regulating valve of the thermostat and its connections. Fig. 6 is an enlarged longitudinal sectional view of the pressure-controlled fuel regulating device. Fig. 7 is a cross-section thereof on the line 7—7, Fig. 6, and Fig. 8 is a side elevation of a portion thereof.

There are, of course, many uses to which a device of this character might be applied with advantage, but as its greatest field of usefulness I have shown it in connection with a motor vehicle, 1 being the seat, 2 the floor and 3 the dash-board of the vehicle.

It is customary to employ in steam vehicles the flasher type of boiler comprising an ordinary coil 4, and I have elected to show the invention in connection with that form of steam generator. To the upper end of such coil the water supply connections, not necessary to illustrate, are made, while the steam generated is drawn from the lower end through a suitable pipe or connection 5—6 and supplied directly to the engine. Ordinarily a portion of this pipe, such as 5, is provided with a thermostat, such, for example, as that shown in Fig. 3 of U. S. Patent 676,790, granted June 18, 1901 to R. H. White, but there are, of course, other forms

that might be employed. This thermostat is designed to control the gasoline or other fluid fuel valve 7, and its effect theoretically is to close this valve and thereby shut off or 5 reduce the amount of fluid passing to the burner when the temperature of the superheated steam passing through section 5 of the steam pipe rises to a predetermined degree, or a degree sufficient to produce that 10 amount of elongation of the thermostat tube which has been previously decided upon as requisite for allowing the valve 7 to close, and when the thermostat tube is again chilled and contracted by the presence of 15 water or moist steam in the pipe section 5, valve 7 is raised more or less from its seat and the supply of fuel to the burner increases. Theoretically, such mechanism should be sufficient to maintain a uniform 20 steam pressure in the generator, but it is well known that in practice such is not the case, for the actual effect at times is to allow the fuel supply to remain on until the coil is heated to a dangerous degree, while at 25 other times the thermostat fails to allow the fuel to pass to the burner even when the steam pressure falls far below normal and a quantity of water is being supplied which, under other circumstances, would suffice to 30 chill the thermostat and allow the fuel valve to open. A plausible explanation of these contrary and theoretically impossible conditions is that in one case the combined effect of the moist steam contiguous to the thermostat tube and the liquid fuel which finds its way into the tube when the fire is started is sufficient to keep the tube contracted and the fuel valve open, although the coil and the outer tube incasing the thermostat may be at 35 40 the same time dangerously overheated; while in the other case the thermostat tube which has once been very highly and greatly overheated, expelling the moist steam from around it and the liquid fuel from within it, 45 takes so long to cool off that the pressure falls far below normal before the tube contracts sufficiently to open the fuel valve. Furthermore, it is found that the thermostat tube does not expand and contract uniformly 50 under uniform conditions, it being observed that the metal when once overheated fails to resume its original shape or length, and this makes it necessary to continually readjust the fuel valve where the conditions are such 55 60 that the thermostat is subjected to excessive extremes of heat and cold. Such are the objections to the purely thermostatic control. A purely steam pressure control of the fuel might under some conditions, as before mentioned, also be objectionable and inefficient; as for example, where the pressure falls and the boiler runs dry, the fire being still on, the boiler would be eventually damaged. To the end that the objections to both of these 65 controls may be overcome, the present in-

vention combines the two systems, though, as before stated, and as will hereinafter more fully appear, the thermostat control is not essential to the operation of the invention under some conditions. When the 70 two systems of control are to be thus combined, steam pressure controlled valve mechanism is interposed between the burner and the thermostatically controlled valve and is connected with the steam generator so as to 75 be actuated by the pressure thereof. This steam pressure controlled valve mechanism is preferably a double acting valve or apparatus which, under normal pressure, provides a free passage for the fuel to the 80 burner, but should the steam pressure either rise or fall below normal or predetermined degrees, it will shut off the fuel regardless of the action of the thermostat, thereby in the case of high pressure preventing excessive 85 pressure, and in the case of low pressure, preventing fire damage to the boiler. In thus combining the two systems of control, the usual outlet connection 8 of the thermostat 90 valve housing 9 is connected to a valve housing 10 in which is contained two valves 11-12, both arranged to control a passage 13, in the opposite ends of which the two valves 11-12 are seated, the valves being 95 preferably assembled or related in such a relation that the seating of one opens the other and vice versa. The valve housing 10 beyond the passage 13 is connected by any suitable connection or pipe 14 with the gas generator or retort 15, and this in turn is 100 connected to the gas nozzle arranged opposite the burner inlet 16 as usual, so that when both valves 11-12 are unseated an equal extent, the maximum flow of fuel to the burner 105 will occur. The valve 11 may be provided with any suitable means for urging it to its seat when not otherwise restrained. The construction embodies a stem 17 which is adjustably connected with the valve 11 by being screw-threaded therein and secured at 110 its adjustment by a jam nut 18, and arranged around this stem between the nut 18 and a guide cap 19 is a coil spring 20 which forces the valve 11 to its seat. The stem 17 is shown as continuing through the valve 11 115 and connected to the valve 12, so that the distance between the two valves may be varied by the adjustment of the valve 11 upon its stem. These two valves are actuated through the intermediary of any suitable agency by the pressure of the steam in the generator 4 in such a way that when the pressure rises beyond the maximum or predetermined degree, the valve 12 will be 120 forced firmly against its seat and the fuel passage 13 completely closed, and on the other hand, when the pressure falls beyond a predetermined degree and the boiler or generator is about to be endangered by the fire, the valve 12 recedes from its seat and per- 125 130

the generator may be considerably raised above that which would be permitted by the ordinary adjustment of spring 26, within a wide range of variation, while the means is such that the apparatus may be readily restored to its original condition where the spring 26 automatically controls the fuel supply, by simply screwing the nut or button 39 upward again on its stem 48.

10 In order that the tension or pressure of spring 20 may be operated at will for holding the valve 11 to its seat with the degree of pressure that might be requisite, some suitable means accessible to the operator and 15 having a proper operative relation to the spring 20 may be employed. As an example of such a means, I have shown a number of removable washers or shims 19^a which are placed under the cap 19, one or more of 20 these being used accordingly as the spring pressure is to be increased or diminished, and it will be seen that by the employment of the proper number of these washers, or by removing them entirely, the resistance 25 which it is desired the spring shall exert against the action of the fluid pressure abutment 24 may be accurately adjusted. It is also apparent that the spring 20 in a large degree, if not wholly, might be made to 30 perform the allotted function of spring 26 in some instances, the action of spring 20 being supplemented by the spring 49, as before mentioned, when the two valves 11 and 12 are not only operatively related, but 35 operatively connected together. With this arrangement it will be seen that should the fire be off and the operator desire to turn it on without waiting for the automatic devices to act, it would simply be necessary 40 for him to press the foot button 39, which would force valve 11 from its seat against the action of spring 20. This button is to be utilized only when the pressure in the generator is below normal and the fuel is 45 turned off. When the pressure in the generator is above the maximum and the fuel is held off by the diaphragm 24 and valve 12, and it should be desired at that time to again turn on the fuel without waiting for 50 the pressure to fall, the foot button 40 is utilized, by means of which, as will be understood, the valve 12 may be pulled away from its seat and both valves held in their unseated position, as will be indicated by the 55 index on indicator 51. At other times the valves 11-12 act automatically to shut off the fuel when the pressure falls below the minimum or rises above the maximum, and, as a consequence, there is never any danger 60 of the thermostat becoming so overheated as to cause it to warp or permanently elongate. As a result, the thermostat retains its sensitive character and is always ready to respond promptly to predetermined variations 65 in temperature and to control the fuel

supply should, through any cause, the steam pressure controlling means fail, as for example, when the extremes between the maximum pressure and minimum pressure at which these latter devices are set to act are so great that the amount of water in the boiler will be insufficient to generate sufficient pressure to reach the maximum shutting off point and yet keep up sufficient pressure to prevent the minimum shutting off point from being reached. In that event the fire would remain on and damage the generator, but for the thermostat, which would act before any excessive overheating of the generator could occur. This condition, of course, could seldom arise, even where the adjustment provided for these extremes of pressure, because when the machine is in use the pumps would be supplying the generator with a quantity of water 85 proportionate to the amount of fuel being consumed and it would only be when the machine is left standing with the fire on, and at very unusual times, that such a contingency could arise, and even then damage 90 might be prevented by the operator shutting off his fuel supply by the usual hand valve 53.

It is of course understood that when the fuel is entirely shut off from the burner, the flame becomes extinguished when the pressure of the generated gas yet remaining in the vaporizer becomes insufficient to project the gas from the nozzle into the burner, although the gas continues to generate in 100 sufficient quantity to create an objectionable odor and escapes from the nozzle, which is set off a short distance from the end of the burner substantially like the nozzle 54 shown in this drawing. In order to prevent 105 this objectionable result, the nozzle is formed with a valve seat 55 on which is located a ball or other suitable valve 56, of sufficient weight to retain the lingering fumes of gas within the nozzle, but which is readily unseated when the gas pressure rises to a sufficient degree to cause the gas to project itself into the burner and ignite. This device is of special advantage where the machine is provided with automatic means, as 110 in this invention, for repeatedly and entirely shutting off the fuel supply.

In order that the invention might be understood by those skilled in the art, the details of an exemplification thereof have 115 been thus specifically described, but

What I claim as new therein and desire to secure by Letters Patent is:—

1. In an apparatus for the purpose described, the combination of a steam generator, a burner for fluid fuel, a pressure controlled means operatively related to the burner and generator for reducing the supply of fuel to the burner when the pressure in the generator reaches a certain degree, 125

mits the spring 20 to force the valve 11 closed, thereby also shutting off the supply of fuel to the burner. It is, of course, apparent also that when the pressure in the generator 4 is normal, both valves 11—12 will be more or less unseated, permitting a normal flow of fuel to the burner for maintaining a normal fire and consequently a uniform pressure. In this exemplification of the invention, the valve 12 is provided with a stem 21 passing through a guide 22 provided with a stuffing box 23 and arranged to be influenced by the diaphragm 24 or other suitable fluid pressure abutment which is located in a diaphragm chamber 25 connected to steam pipe 6 in such a manner that the steam pressure of the generator deflects the diaphragm and moves the valves 11—12 with reference to their seats as before explained, and when the pressure falls, the diaphragm is returned to its former position by a spring 26 or other suitable cushion whose power of resistance is so proportioned as to overcome the pressure within the generator until it reaches that degree which has been previously determined upon as the degree of pressure at which this valve 11 shall open without entirely closing the valve 12. The diaphragm 24 acts directly against a head 27 which serves as an abutment for one end of the spring 26, whose other end rests against a plate 28 through which passes a stem 29 connected to the head 27 at its lower end. The upper end of this stem passes through a suitable guide 30 which is screw threaded in the end of a casing 31 inclosing the spring 26, the guide being formed with wrench sockets 32 whereby it may be adjusted with respect to the plate 28 and thereby increase the degree of pressure of the spring 26 against the diaphragm 24. In the upper end of stem 29 is arranged an adjusting screw 33 provided with a notched disk 34, or other suitable means whereby the screw 45 may be turned. In this example of the invention, the edge of the disk is accessible to the fingers of the operator through the open sides of a yoke or frame 35 which is secured to the casing 31 and carries the guide 22, and the disk 34 is locked at its adjustment by a pair of dogs 36—37 embracing one of the bars of the yoke 35 and projecting inwardly from a spring 38 on which they are formed. The lower end of the stem 21 is given support upon the upper end of the screw 33, whose head is pointed on its upper side, although squared at its edges to fit within a corresponding socket in the disk 34, so that by rotating the disk 34, the valve 11 may be unseated at an earlier or later period, as may be required with respect to the movement of the diaphragm 24. There are, of course, times when it may be necessary or desirable to control the supply of fuel to the burner manually without waiting

for these automatic devices to act, as before mentioned, and to that end the automatic devices are provided with suitable means accessible to the driver or operator, whereby they may be opened or closed such, for example, as two foot buttons 39—40. These are connected to one arm 41 of a lever pivoted at 42 to the yoke 35, and having its other arm connected to the stem 21. A convenient means of effecting this connection 75 consists in providing the lower end of stem 21 with a screw threaded portion 43 of liberal dimensions, to which is clamped a divided lug 44 having trunnions 45 located within the embrace of bifurcated jaws 46, 80 constituting the other arm of the said lever. The arm 41 of the lever is provided with an adjustable extension 47 which is pivoted to the lower end of a rod 48, and the upper end of this rod passes through the floor of the 85 vehicle and carries foot button 39, under which is arranged a cushion or spring 49 adapted to lift rod 48 and return the valves 11—12 to the position shown in Fig. 6, should the spring 20 fail to do so. Rod 48 90 is also connected pivotally to a lever 50 to which the foot button 40 is also pivoted. Rod 50 may be provided with an indicator 51 extending upwardly through the floor with its end arranged in reading relation to 95 a scale 52 on the dash board bearing words or characters indicating the positions of the valves 11—12 with respect to their seats. Occasions arise in the operation of such devices when it might be desired to keep the 100 fire on a longer time than would be ordinarily permitted by the automatic pressure regulator. It has before been explained that by pressing the foot button 39, the valve 11 may be forced from its seat and by proper 105 manipulation both valves 11 and 12 held from their seats, or valve 12 might be pressed to its seat for completely closing the fuel passage, but should it be desired to keep these valves 11 and 12 open and allow 110 the fire to remain on, as just mentioned, the result might be conveniently accomplished by simply screwing the foot button 39 further downward on its rod or stem 48, thereby compressing the spring 49 which induces 115 greater upward strain against the rod 48 and thereby resists the pressure of the steam generator against the fluid pressure abutment or diaphragm 24, restraining the floor pressure arm from closing the valve 12. 120 This it will be seen is a simple method of accomplishing this desirable result without in any manner altering the adjustment or tension of the spring 26, which, as before explained, is set or adjusted to resist the boiler pressure up to the point where it is desired to have the valve 12 closed under ordinary conditions. It is also seen that by a proper adjustment of the foot button or nut 125 39 on its stem 48, the working pressure of 130

said means embodying a fuel passage, two valves operatively related whereby one moves the other for closing the passage alternately, and means whereby said valves will be actuated by the generator pressure.

2. In an apparatus for the purpose described the combination of a steam generator, a burner for fluid fuel, a pressure controlled means operatively related to the burner and generator for reducing the supply of fuel to the burner when the pressure in the generator reaches a certain degree, said means embodying a fuel passage, two valves operatively related whereby one moves the other for closing said passage alternately, means whereby said valves are actuated by the generator pressure, and means whereby both of said valves may be actuated manually regardless of the generator pressure.

3. In an apparatus for the purpose described the combination of a steam generator, a burner for fluid fuel, and a pressure controlled means operatively related to the burner and generator for reducing the fuel supply to the burner when the pressure in the generator reaches a certain degree, said means embodying a fuel passage, two valves connected together through said passage for alternately closing the ends thereof, and two manually actuated members operatively connected with said valves for respectively moving them toward their seats.

4. In an apparatus for the purpose described the combination of a steam generator, a burner for fluid fuel, pressure controlled means operatively related to the burner and generator for reducing the fuel supply to the burner when the pressure in the generator reaches a certain degree, said means embodying a fluid pressure abutment exposed to the pressure of the generator, a valve movable independently of said abutment for controlling the fuel supply, means for actuating the valve manually at will, and means whereby the movement of the abutment may be imparted to the valve, embodying means for adjusting the position of the valve with relation to the abutment, said valve adjusting means being operative independently of said means for moving the valve manually.

5. In an apparatus for the purpose described the combination of a steam generator, a burner for fluid fuel, pressure controlled means operatively related to the burner and the generator for reducing the fuel supply to the burner when the pressure in the generator reaches a certain degree, said means embodying a fluid pressure abutment subjected to the pressure of the generator and a valve, a manually operating means for said fluid pressure abutment adapted to resist the action of the generator pressure thereagainst for permitting the said valve

to move independently of the generator pressure, and a spring for resisting the operation of said manually operated means and also resisting the action of the generator pressure against said abutment.

6. In an apparatus for the purpose described the combination of a steam generator, a burner for fluid fuel, pressure controlled means operatively related to the burner and the generator for reducing the fuel supply to the burner when the pressure in the generator reaches a certain degree, said means embodying a fluid pressure abutment subjected to the pressure of the generator and a valve arranged to be closed by said abutment, a manually operated means for moving said abutment against the pressure of the generator and permitting the valve to open, embodying a foot button, a spring for supporting said foot button against depression, and means for regulating the tension of said spring.

7. In an apparatus for the purpose described, the combination of a steam generator, a burner for fluid fuel, a pressure controlled means operatively related to the burner and generator for reducing the fuel supply to the burner when the pressure in the generator reaches a certain degree, said means embodying a valve and a spring for resisting the pressure in the generator to permit said valve to be opened, a foot button operatively connected with said valve for opening it manually against the pressure in the generator, a second spring operatively connected with the foot button and acting in a direction to counter-act the pressure of said first spring, and means whereby the pressure of said second spring may be varied and the resultant effect of the generator pressure against said valve accordingly varied.

8. In an apparatus for the purpose described, the combination of a steam generator, a burner for fluid fuel, a pressure controlled means operatively related to the burner and generator for increasing the fuel supply when the pressure in the generator reaches a certain degree, said means embodying a fuel passage, a valve closing said passage, a spring for holding said valve seated, a fluid pressure abutment exposed to the pressure of the generator for opening said valve but said abutment being disconnected from said valve so as to be movable in one direction independently thereof, and a manually operative means for opening said valve at will independently of said abutment and permitting the spring to close the valve by moving the abutment in a direction against the generator pressure.

9. In a fuel regulator for steam boilers the combination of a steam flash boiler or generator, means for admitting water to the upper part of said generator, a thermostatic fuel regulator arranged in the steam passage

of the generator near its lower end, a burner having its fuel supply controlled by said thermostatic regulator, and a steam pressure regulator operatively connected with the steam generator and also operatively related to said burner for controlling the fuel supply thereto, said pressure regulator embodying means for shutting off the fuel supply when the pressure in the generator rises 10 above a certain degree, and separate means for shutting off the supply of fuel when the pressure in the generator falls below a certain degree.

10. In an apparatus for the purpose described the combination of a flash steam generator, a burner for fluid fuel, pressure controlled means operatively related to the burner and communicating with the generator for reducing the supply of fuel to the 15 burner when the pressure in the generator increases above a certain degree, and a thermostat also operatively related to the burner and subjected to the heat of the steam generator for controlling the supply of fuel to the 20 burner, said pressure controlled means embodying a diaphragm chamber with which the steam generator communicates, a diaphragm in said chamber, a headed stem having the head thereof resting against the dia- 25 phragm, a spring encircling the said stem and bearing against said head, a fuel passage leading to the burner and having a valve seat, a valve for closing said passage, a stem for said valve arranged in axial alinement 30 with the first said stem and being independent thereof and adapted to receive motion therefrom for closing said valve when the dia- 35 phragm is moved against the resistance of said spring, and means situated between the 40 adjacent ends of said stems adjustably supported by one stem and engaging the other for adjusting them relatively.

11. In an apparatus for the purpose described, the combination of a flash steam generator, a burner for fluid fuel, pressure controlled means operatively related to the burner and communicating with the generator for reducing the supply of fuel to the burner when the pressure in the generator 45 reaches a certain degree, and thermostatic means also operatively related to the burner and communicating with the generator for controlling the supply of fuel to the burner, said pressure controlled means embodying a 50 diaphragm chamber with which the steam generator communicates, a diaphragm in said chamber, a stem arranged to be moved in one direction by said diaphragm, a spring for moving said stem in the opposite direc- 55 tion against the resistance of the generator pressure, a fuel passage leading to the burner and having a valve seat, a valve for closing said passage, a stem arranged in axial alinement with the first said stem and connected 60 to said valve for receiving the longitudi- 65

nal movement of the first said stem and thereby closing said valve, said stems being independent, and manually operative means connected with the stem of the valve for opening and closing the valve at will.

12. In an apparatus for the purpose described, the combination of a steam generator, a burner for fluid fuel, a pressure controlled means operatively related to the burner and generator for increasing the fuel supply when the pressure in the generator reaches a certain degree, said means embodying a fuel passage, a valve closing said passage, a spring adapted to open said valve, a fluid pressure abutment exposed to the pressure of the generator for closing said valve, said abutment being disconnected from said valve so as to be movable in one direction independently thereof, and a manually operative means connected with said valve for closing the same at will independently of said abutment.

13. In an apparatus for the purpose described, the combination of a flash steam generator, a burner for fluid fuel, pressure controlled means operatively related to the burner and communicating with the generator for reducing the supply of fuel to the burner when the pressure in the generator reaches a certain degree, said pressure controlled means embodying a diaphragm chamber with which the steam generator communicates, a diaphragm in said chamber with stem arranged to be moved in one direction by said diaphragm, a spring for moving said stem in the opposite direction against the resistance of the generator pressure, a fuel passage leading to the burner and having a valve seat, a valve for closing said passage, a stem arranged in axial alinement with the first said stem and connected with said valve for receiving the longitudinal movement of the first said stem and thereby closing said valve, said stems being independent, and manually operative means connected with the stem of the valve for opening and closing the valve at will.

14. In an apparatus for the purpose described, the combination of a flash generator, a burner for fluid fuel, pressure controlled means operatively related to the burner and communicating with the generator for reducing the fuel supply to the burner when the pressure in the generator reaches a certain degree, said pressure controlled means embodying a diaphragm chamber with which the steam generator communicates, a diaphragm in said chamber, a stem arranged to be moved in one direction by said diaphragm, a spring for moving said stem in the opposite direction against the resistance of the generator pressure, a fuel passage leading to the burner and having two valve seats, two alternately closing valves arranged to engage said seats respec- 120 125 130

tively, means whereby the closing of one of said valves opens the other, a stem arranged in axial alinement with the first said stem and connected with one of said valves for receiving the longitudinal movement of the first said stem and thereby closing the valve to which the second said stem is connected, said stems being independent, and manually operating means connected with the said 10 stem of the valve for closing that valve at will.

15. In an apparatus for the purpose described, the combination of a steam generator, a burner for liquid fuel, a pressure controlled means operatively related to the burner and generator for controlling the fuel supply when the pressure in the generator fluctuates between certain degrees, said means embodying a fuel passage, valves for 20 closing said passage at each end adjustable with respect to each other, a spring adapted to open one of the said valves, a fluid pressure abutment exposed to the pressure of the generator for opening another of said valves, said abutment being disconnected from the valves so as to be moved in one direction independently thereof, and a manually operative means connected with one of 25

said valves for closing the same at will independently of the abutment.

16. In an apparatus for the purpose described; the combination of a steam generator, a burner for liquid fuel, a pressure controlled means operatively related to the burner and generator for controlling the fuel supply when the pressure in the generator fluctuates between certain degrees, said means embodying a fuel passage, adjustable spaced valves for closing said passage at both ends, a spring adapted to open one of the said valves, a fluid pressure abutment exposed to the pressure of the generator for opening another of said valves, said abutment being disconnected from the valves so as to be moved in one direction independently thereof, and means for closing one of the said valves at will and independently of the said fluid controlled means.

In testimony whereof I have signed my name to this specification, in the presence of 50 two subscribing witnesses, on this 8th day of April A. D. 1907.

ROBERT MIEHLE.
